UNITED STATES PATENT OFFICE.

CHARLES H. WEISGERBER, OF PHILADELPHIA, PENNSYLVANIA.

DESIGN FOR A COIN BANK OR SIMILAR ARTICLE.

Application filed January 30, 1929. Serial No. 29,854. Term of patent 14 years.

To all whom it may concern:

Be it known that I, CHARLES H. WEISGERBER, a citizen of the United States, residing at Philadelphia, in the county of Philadelphia and State of Pennsylvania, have invented a new, original, and ornamental Design for Coin Banks or Similar Articles, of which the following is a specification, reference being had to the accompanying drawings, forming a part thereof.

Fig. 1 is a plan view of a coin bank or similar article showing my new design.

Fig. 2 is a side elevational view of the same.

Fig. 3 is an elevational view of the side opposite to that shown in Fig. 2.

Fig. 4 is an elevational view of the left hand end of Fig. 2.

Fig. 5 is an elevational view of the right hand end of Fig. 2.

I claim:

The ornamental design for a coin bank or similar article substantially as shown.

CHARLES H. WEISGERBER.
